No. 486,280. In Germany October 15, 1929

7 Claims. (CL 260—156)

The present invention relates to the production of alcohols.

By the destructive oxidation of liquid or solid hydrocarbons, a mixture of different oxygen-containing products, such as acids, lactones, esters, aldehydes, ketones and the like which usually also contain unattached initial material is generally obtained as the oxidation product. When obtained under the said liquid-phase conditions, the oxygenated products of the liquid-phase oxidation will contain about the same number of carbon atoms as the initial materials, of which paraffin is known to contain hydrocarbons containing from about 12 to 36 carbon atoms, mainly from about 10 to about 24 carbon atoms (compare for example Berichte der Deutschen Chemischen Gesellschaft, vol. 40, (1907), page 4779). In accordance with the said statements water-insoluble fatty acids containing from 10 to about 35 carbon atoms, mainly from 11 to 24 carbon atoms, have been identified in the liquid phase oxidation products from paraffin (according to the aforesaid citations, Chemiker Zeitung 49 (1920), page 311, and Zeitschrift fur angewandte Chemie 1918, page 69). Similarly, alcohols in the said oxidation products contain from about 10 to 25 carbon atoms (see Journal of the Chemical Society 1926, page 2377), lauryl, myristyl, palmityl and stearyl or octadecyl alcohols together with alcohols containing 22, 24 and 25 carbon atoms having been found besides the corresponding myristic, palmitic, isopalmitic, stearic and arachic acids, the alcohols having from about 12 to about 20 carbon atoms constituting generally the predominant portion of the whole mixture of alcohols.

We have now found that a product consisting mainly of the higher members of the aliphatic alcohol series is readily obtained from the mixture produced in the manner already known by the destructive oxidation of difficultly volatile, i. e. liquid or solid hydrocarbons in the liquid state as for example with gaseous oxidizing agents containing free oxygen such as air or mixtures of oxygen with carbon dioxide or nitrogen, with or without the employment of catalysts, by subjecting the said mixture obtained by oxidation, or constituents containing oxygen separated therefrom, as for example the neutral fraction consisting of esters, ketones and the like, to a hydrogenation at super-atmospheric pressure with large quantities of hydrogen, or gaseous mixtures containing hydrogen. The hydrogenation is carried out with hydrogen at elevated pressures usually ranging up to about 100 atmospheres, in the presence of a hydrogenating catalyst, as for example finely divided metallic

nickel, and at elevated temperatures ranging from about 150° to 230° C., but somewhat higher or lower temperatures such as up to about 250° and down to about 100° C. may also be employed. The pressure employed should generally exceed 10 atmospheres since otherwise the reaction would proceed too slowly for practical purposes and pressures above 300 atmospheres are generally not employed since this method of working would require particularly costly apparatus. The absorption of hydrogen is completed in a short period of time. The duration of the reaction depends on the kind of the initial material and on the working conditions employed. For example with oxidation products from paraffin wax a hydrogenation effected at 200° C. and at a pressure of 50 atmospheres in the presence of nickel as a catalyst is already completed in three hours. The separation of the alcohols formed from the unattacked initial material and any acids present may be effected in any usual and convenient manner by physical or chemical methods, as for example by the employment of solvents having a selective dissolving power, by distillation or by esterification.

Though the initial oxidation products are of a most heterogeneous composition the reduction stops against all expectation at the alcohol stage and practically no hydrocarbons are formed.

Alcohols having a more or less high melting point are obtained according to the nature of the initial materials employed for the oxidation, such as petroleum fractions boiling above 180° C., as for example middle oils, liquid, hard or soft paraffins and the like. For example, by employing hard paraffin wax as the initial material in the oxidation, a product is obtained the melting point of which is above 30° C. In most cases mixtures of alcohols having a very high molecular weight are obtained, the alcohols from oxidation products of the said petroleum fractions containing an average of about 10 carbon atoms and those from paraffin waxes an average of about 15 carbon atoms. Depending on the content of the initial materials for the hydrogenation of unoxidized hydrocarbon the hydroxyl value of the final products will vary between 100 and 200.

The following examples will further illustrate the nature of this invention, but the invention is not restricted to these examples. The parts are by weight.

Example 1

700 parts of the neutral oxygen-containing constituents separated from an oxidation product

obtained by treatment of hard paraffin wax with air at a temperature of about 160° C. and containing from about 35 to 40 per cent of oxygenated constituents having a neutral reaction are treated for some hours in a stirring autoclave with hydrogen at 200° C. under a pressure of 30 atmospheres in the presence of finely divided metallic nickel, and in this manner 5 parts of hydrogen are absorbed. The nickel catalyst is then filtered off. A pure white mixture consisting of higher wax alcohols is obtained and may be further purified by the usual methods, as for example by steam distillation. The mixture has hydrophilous properties and is eminently suitable for the preparation of ointments, esters, sulphonation products for wetting and cleansing agents and the like. The hydroxyl value of this mixture of alcohols amounts to from about 120 to 130.

Example 2

1000 parts of an oxidation product which has been prepared by blowing paraffin oil in the presence of 1 per cent its weight of manganese naphthenate at 160° C. with air and which contains about 35 per cent its weight of free carboxylic acids, are subjected in an autoclave and in the presence of 5 parts of nickel deposited on 15 parts of kieselguhr to the action of hydrogen at a temperature of 180° C. for 4 hours while stirring, after hydrogen has been pressed into the autoclave until a pressure of 50 atmospheres has been attained. After filtering off the catalyst the last traces of nickel are washed out from the product by means of dilute aqueous sulphuric acid. After separating the saponifiable constituents of the products by a treatment with aqueous caustic soda at about 100° C. and drawing off the aqueous soap solution, about 30 per cent of the original oxidation product is obtained as a mixture of high-molecular liquid alcohols which has a hydroxyl value of 160.

Example 3

1000 parts of an oxidation product prepared by blowing hard paraffin wax with air at about 160° C. are treated with hydrogen at 250° C. and 50 atmospheres pressure in an autoclave after adding 10 parts of finely divided cobalt which has been prepared by heating cobalt carbonate in a current of hydrogen at 350° C. for 36 hours. After filtering off the catalyst the product is washed with dilute aqueous sulphuric acid for removing traces of cobalt from the reaction product. After separating saponifiable constituents (free acids, lactones and esters) from the reaction product a semi-solid mixture of alcohols is obtained in a yield of 65 per cent of the original oxidation product, which may find useful application in the production of salves or ointments or for the production of wetting, cleansing or emulsifying agents by sulphonation.

By the aforescribed treatment 40 per cent by weight of the esters and free acids contained in the oxidation product are converted into alcohols which appears from the following figures:

	Acid value	Saponification value	Unsaponifiable matter (per cent)	Hydroxyl value of unsaponifiable matter
Initial material	78.5	142.3	47.0	25.3
Reaction product	11.5	64.6	65.2	104.8

Example 4

1000 parts of an oxidation product, prepared by

blowing paraffin oil in the presence of 1 per cent its weight of manganese naphthenate with air at 160° C. and which contains about 35 per cent by weight of free carboxylic acids is heated, while stirring, together with 5 parts of nickel deposited on 15 parts of kieselguhr, at 180° C. and 50 atmospheres which pressure is attained by pressing hydrogen into the autoclave. After filtering off the catalyst any traces of nickel in the reaction product are washed away with the aid of dilute sulphuric acid. After separating off the saponifiable constituents (free acids, lactones and esters) a mixture of high molecular liquid alcohols is obtained in a yield of about 30 per cent of the original oxidation product.

Example 5

1000 parts of an oxidation product prepared by blowing soft paraffin wax at about 150° C. with air, from which free carboxylic acids have been removed with the aid of aqueous soda solution, are mixed with 5 parts of nickel deposited on 15 parts of kieselguhr and the whole is then heated for four hours at 200° C. in an autoclave while stirring after hydrogen has been pressed into the latter until a pressure of 60 atmospheres is attained. The nickel catalyst is then filtered off and after separating the saponifiable constituents (esters, lactones and acids) a mixture of semi-solid high molecular alcohols is obtained which possesses a hydroxyl value of 140.

What we claim is:—

1. The process for the production of products consisting mainly of mixtures of the higher members of the aliphatic alcohol series which comprises heating the products, comprising non-aromatic long-chain acids, esters and carbonyl compounds from a destructive oxidation of difficultly volatile hydrocarbons in the liquid phase by means of a gaseous oxidizing agent containing free oxygen, in the presence of hydrogen and of a hydrogenating catalyst containing an element selected from the iron group at a pressure above atmospheric pressure.

2. The process for the production of products consisting mainly of mixtures of the higher members of the aliphatic alcohol series which comprises heating the products, comprising non-aromatic long-chain acids, esters and carbonyl compounds from a destructive oxidation of difficultly volatile hydrocarbons in the liquid phase by means of a gaseous oxidizing agent containing free oxygen, in the presence of hydrogen and of a hydrogenating catalyst containing an element selected from the iron group at a pressure above atmospheric pressure to a temperature between about 100° and 250° C.

3. The process for the production of products consisting mainly of mixtures of the higher members of the aliphatic alcohol series which comprises heating the products, comprising non-aromatic long-chain acids, esters and carbonyl compounds from a destructive oxidation of difficultly volatile paraffin hydrocarbons in the liquid phase by means of air, in the presence of hydrogen and of a hydrogenating catalyst containing an element selected from the iron group at a pressure above atmospheric pressure to a temperature between about 150° and 230° C.

4. The process for the production of products consisting mainly of mixtures of the higher members of the aliphatic alcohol series which comprises heating the products, comprising non-aromatic long-chain acids, esters and carbonyl

compounds from a destructive oxidation of difficultly volatile paraffin hydrocarbons in the liquid phase by means of air, in the presence of hydrogen and of nickel at a pressure above 10 atmospheres to a temperature between about 150° and 230° C.

5. The process for the production of products consisting mainly of mixtures of the higher members of the aliphatic alcohol series which 10 comprises heating the products, comprising non-aromatic long-chain acids, esters and carbonyl compounds from a destructive oxidation of paraffin wax in the liquid phase by means of air, in the presence of hydrogen and of nickel at a pressure between about 20 and 100 atmospheres.

15. 6. The process for the production of products consisting mainly of mixtures of the higher members of the aliphatic alcohol series which

comprises heating a fraction of reducible neutral compounds of a product, comprising long-chain esters, and carbonyl compounds from a destructive oxidation of paraffin wax in the liquid phase by means of air, in the presence of hydrogen and 5 of nickel at a pressure between about 20 and 100 atmospheres.

7. Mixtures of alcohols having hydroxyl values between 100 and 200 the said alcohols having an average of carbon atoms between 10 and 15, obtained by the catalytic hydrogenation of products from the destructive oxidation of difficultly volatile hydrocarbons in the liquid phase by means of a gaseous oxidizing agent containing free oxygen.
